UNITED STATES PATENT OFFICE

KARL BAUMANN, OF URMSTON, ENGLAND, ASSIGNOR TO WESTINGHOUSE ELECTRIC & MANUFACTURING COMPANY, A CORPORATION OF PENNSYLVANIA

LABYRINTH GLAND PACKING

Application filed April 13, 1928, Serial No. 269,816, and in Great Britain April 28, 1927.

The invention relates to labyrinth gland packing for use between relatively movable parts of a machine as for instance, between a turbine shaft and the part of a turbine casing through which it passes.

The main object of the invention is to provide an improved construction of such packing which, while possessing the advantage that the contiguous packing members automatically tend to separate if rubbing occurs therebetween, as is obtained by packings such as described in my Patent 1,708,044, granted April 9, 1929, admits of more compact construction than forms hitherto proposed.

Another and important object is to provide a form of packing which is simple and compact and also inexpensive to manufacture.

Labyrinth gland packings usually comprise a number of annular strips so arranged as to provide a devious path for the steam or other fluid which tends to pass from the high pressure to the low pressure side of the gland and for the purpose of considering the construction and arrangement of the packing strips it is convenient to refer to the cross-sectional form which they present on a plane containing the axis of rotation. The strips considered in this manner are more or less of cantilever form, one end being free, and the other end, conveniently termed the "root" being secured directly or indirectly to the appurtenant gland member. It is in this sense that the term "end" is hereinafter employed or the cross-section considered where stated.

The labyrinth gland packing in accordance with the present invention comprises coaxial sets of annular strips secured at one end and of substantially cylindrical form over at least a portion of their axial length adjacent their free ends, said cylindrical portions of any one set being interleaved with those of an adjacent set so that the strips of said one set terminate near the fixed ends of the adjacent set of strips, the free end of each strip lying close to the opposed outer surface of the adjacent strip on the inside but being spaced further from the inner surface of the adjacent strip on the outside.

Since in the labyrinth packing constructed

as set forth above, the constrictions are formed between the inner surfaces near the free ends of the strips and the outer surfaces close to the fixed ends thereof, upon the occurrence of rubbing contact between the strips, the circumferential dimensions of the free ends of the strips will immediately increase due to local heating, while the fixed ends of the strips will remain substantially unaffected, partly because of their thickness and the short effective length of cantilever, and partly because the heat is rapidly conducted away through the adjacent masses of metal. Also, since the interleaved portions of the annular strips do not substantially depart from the cylindrical form they may be packed very closely together. An extraordinary large number of constrictions may thus be provided in a given cross section of the packing and in view of the sensitivity of the self-adjusting action set up upon the occurrence of rubbing contact, the clearances at the constrictions may be made extremely small without fear of excessive wear upon the parts under normal conditions of service.

The outer circumferential surface of each strip may be stepped by increasing the external diameter of the strip adjacent its fixed end, such stepped portion serving to provide a constriction in conjunction with the inside of an adjacent strip, and if desired more than one such enlargement may be provided upon each strip.

The invention also contemplates constructions whereby in addition to providing external enlargements as above stated the internal diameter of each strip is reduced at one or more points somewhat removed from the free end thereof for the purpose of providing constrictions in conjunction with the outside of an adjacent strip and at the same time thickening the strip towards the root while leaving it relatively thin at its free end.

The extremities of the strips and/or the portions at the roots of the strips may be shaped, for example, by chamfering the end surface of the strip or conically shaping said root portion, the inclined surface thereby presented being utilized to provide constrictions, the passage area of which may be ad-

justed, if desired, by axial displacement of the strips or sets of strips.

A gland according to the invention may comprise some sets of strips by which adjusting of the constriction is possible, while other sets of strips permit of axial displacement without varying the width of the constrictions.

Constructions of packing according to the invention are illustrated on the accompanying sheet of drawings in which:

Figs. 1, 2 and 3 are enlarged detail sectional views indicating three possible forms which the packing strips may take;

Fig. 4 shows sets of strips of the form shown by Figs. 1 and 2 assembled together; and,

Fig. 5 illustrates one method of mounting a series of packing members according to the invention between a shaft and the casing portion through which it passes.

All the figures represent cross sections taken on a plane containing the axis of rotation, which axis is parallel to the top and bottom edges of the sheet and below the figures.

As shown in Fig. 1 annular strips 1a, which present a cantilever form in cross section appertaining to one of the relatively rotatable members 27, are interleaved with similar strips 1b, appertaining to the other member 28. The strips are truly cylindrical and so arranged that the free ends 2a, 2b, of the respective strips terminate near the fixed ends 3a, 3b of the strips with which they are interleaved and lie close to the opposed outer surface 3a, 3b of the internally adjacent strip so as to provide constrictions 4 therebetween.

A considerable space 5, however, exists between the free end of each strip and the inner surface of the externally adjacent strip, and it will be readily appreciated that should rubbing contact occur at a constriction 4, the frictional heating of the free end of the strip at such constriction will immediately cause the end of said strip to expand so as to lessen the contact pressure or eventually to reopen said constricted passage. There is no substantial expansion of the inner cooperating strip at the surface 3a or 3b, first, because the greater amount of adjacent metal conducts the heat away more rapidly, and second, because the member 27 or 28, which is not appreciably heated, holds the attached end of the strip against expansion.

It will be observed that in the construction shown the desired effect is obtained merely by increasing the external diameters of the strips adjacent the fixed ends so as to provide stepped portions 6 where the constrictions 4 are formed. The strips are thus strengthened near the roots, where the maximum strength is required, and moreover the radial pitch or distance between the constrictions 4 may be reduced to the minimum

thickness of metal which may be safely permitted at the root, in spite of the fact that a free space 5 must be left externally of the free end of each strip.

In the construction above described and shown in Fig. 1, a certain amount of relative axial movement between strips 1a and 1b will cause no alteration of the width of the constrictions 4. In constructions such as shown in Figs. 2 or 3, however, constrictions are formed between surfaces, some of which are conical, and in these cases the width of such constrictions can be adjusted in a relatively simple manner.

Fig. 2 shows strips having chamfered extremities 8 associated with the edges 9' of enlargements 9 at the roots of the adjacent strips on the inside so as to provide constrictions 10, the width of which may be altered by relative axial movement of the members to which the strips are secured. In addition to the constrictions 10, further constrictions 11 are provided between the inner surface of the free end portion of each strip and the outer surface of the adjacent strip on the inside in a similar manner to that shown in Fig. 1.

Fig. 3 shows a construction in which adjustable clearances 12 are afforded between the extremities of the strips and conical portions 13 formed at the roots of the respectively adjacent strips on the inside. Further constrictions 14 are provided between the outer surface of a portion of each strip near the root thereof, having a greater external diameter than the free end of the strip, and the inner surface of the adjacent strip on the outside, the internal diameter of which is reduced at a point somewhat removed from the free end.

Fig. 4 shows sets of packing strips having respectively the forms shown in Figs. 1 and 2 assembled in operative relation. The packing strips extend laterally from annular members 15, 16 and 17 with which they are integral, the central member 16 having on one side a set of strips like those shown in Fig. 1 and associated with similar strips carried by member 15, and on the other side a set of strips like those shown in Fig. 2 and associated with similar strips carried by member 17. Thus, relative axial movement between annular members 15 and 16 may take place without alteration of the width of the constrictions or clearances therebetween, whereas certain of the constrictions between the strips of members 16 and 17 can be adjusted by relative axial movement of said members.

It will be observed that the strips all present a parallel-sided stepped cross sectional form with the exception of the outer strips of members 15 and 17, which are plain.

Fig. 5 shows a convenient method of mounting packing members to form a gland between the shaft 18 and casing portion 19

through which it passes. The gland comprises a series of annular members 20 each having two sets of strips, and annular members 21, each having a single set of strips, associated with the outer sets of said series. In assembling the gland, the annular members 20, 21 with appropriate spacing rings or segments 22 are passed over the end of shaft 18 and moved axially into their position in which they are keyed and are then clamped between collars 23, 24 and detachable clamping members 25, 26 mounted on the shaft and casing respectively.

In connection with Fig. 5 it should be noted that no claim is made to the herein above described method of assembly per se.

It will be readily appreciated from the foregoing description that the invention provides a labyrinth gland packing whereby a large number of restrictions are provided in a packing of very small dimensions, sufficient clearance being provided externally of the free end of each strip to permit of ready expansion thereof upon heating, while one or 25 more constrictions are afforded in conjunction with the inner periphery of each said free ends. At the same time the fixed ends of the strips are stiffened to the necessary degree so that the expansion upon local heating is limited, and the heat thereof quickly dissipated through the adjacent metal mass.

It will be apparent from the drawings that the packing strips are of simple form and without sharp edges or undercut recesses. 35 They may, therefore, be quickly and easily machined, thereby reducing the cost of manufacture.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are imposed by the prior art or as are set forth in the appended claims.

What I claim is:—

1. Labyrinth gland packing for two relatively rotatable members comprising a plurality of concentric substantially cylindrical packing strips carried by one member and a plurality of similar strips carried by the other member and interleaving with the first-mentioned strips, said strips being sufficiently thin and axially elongated to provide radial flexibility of the free ends, each of said strips, other than the outermost, being extended radially outwardly at its fixed end to cooperate with the integral free end of the adjacent outer strip to provide a fluid seal constriction, there being sufficient clearance between the free end of each strip and the fixed end of the externally adjacent strip to avoid contact upon expansion of the free end.

65 2. Labyrinth gland packing according to

claim 1 comprising at least two pairs of interleaved sets of strips, in one pair of which the cooperating strips have cylindrical surfaces forming the constrictions, so that relative axial movement of the strips may take place without alteration of the width of the constrictions thereof, whilst in the other pair, the strips of one set have conical surfaces and the strips of the other set have edges cooperating with the conical surfaces to form at least some of the constrictions, so that relative axial movement of the strips serves to alter the width of the last-mentioned constrictions, each rotating member carrying the strips of one pair extending in one axial direction and the strips of the other pair extending in the opposite axial direction.

3. Labyrinth gland packing for two relatively rotatable members comprising a plurality of concentric substantially cylindrical packing strips fixed at one end to one member and a plurality of similar strips carried by the other member and interleaving with the first-mentioned strips, said strips being sufficiently thin and axially elongated to provide radial flexibility of the free ends, the marginal free end portion of one strip being formed of reduced thickness by increasing the diameter of the inner side thereof, and the adjacent inner strip being provided with an enlarged portion on the outer side thereof cooperating with the inner diameter of said one strip adjacent the portion of reduced thickness to provide a packing clearance and being further provided with a second enlarged portion cooperating with the inner side of the free end to provide a second packing clearance, there being sufficient clearance between the free end of each strip and the fixed end of the externally adjacent strip to avoid contact upon expansion of the free end, one of the surfaces providing the second packing clearance being substantially conical, whereby said second packing clearance may be varied by relative axial movement of said members.

In testimony whereof, I have hereunto subscribed my name this 20th day of March, 1928.
